GASOLINE ECONOMIZER

Louis Gaddoni, New Rochelle, N. Y.

Application November 28, 1945, Serial No. 631,241

2 Claims. (Cl. 137—480)

1

This invention relates to improvements in gasoline economizers more particularly of the type disclosed and claimed in my application Ser. No. 546,010, filed July 21, 1944, now Patent No. 2,581,478, January 8, 1952.

In that application I have disclosed a valve casing consisting of two elements one of which is adapted to be attached to an intake manifold and to be threaded into the other element which is provided with a valve guide and a valve seat for cooperation with an elongated valve provided with longitudinally extending tapered air-metering grooves in its outer surface. The valve is pressed against its seat by a spring interposed between the valve and the first-mentioned element with sufficient pressure to cause it to remain seated during cranking operations. By adjustment of the compression of the spring, the valve may be controlled to admit and meter air in proper quantities during idling and running operations.

Objects of this invention are the provision of improved means for effecting a fine and accurate adjustment of the valve, improved means for lockingly maintaining such adjustment, improved means for admitting air in larger volume as the suction pressure increases and improved means for preventing fluttering of the valve in response to the normal rapid variations from the mean of the suction pressure established in the intake manifold under any given unchanging conditions of operation.

Other objects of this invention will appear from the following description taken in connection with the drawings, in which,

Figure 1 shows in side elevation an engine, an intake manifold and a carburetor diagrammatically, with my improved air intake valve mounted on the manifold;

Figure 2 is an axial section through the air intake valve;

Figure 3 is a similar section showing the air intake valve in an operated position;

Figure 4 is a section on the line 4—4 of Figure 2; and

Figure 5 is a detail showing a preferred relationship between the adjusting and locking threads.

In Figure 1 I have shown diagrammatically a gasoline engine at 6, an intake manifold at 7, a carburetor at 8 and my improved air intake valve at 9 mounted horizontally on the manifold at the point where the stream of explosive mixture enters the horizontal distributing section of the manifold. The valve may be mounted in a ver-

2

tical position in the center of the top wall of the distributing section of the manifold, or it may be mounted anywhere between the throttle 10 and the manifold proper, or it may be connected to any vacuum pipe, such as that leading to the windshield wiper, the gear shift booster, etc.

The throttle is of the usual construction and is operated by the usual accelerator pedal and an adjustable stop 11 is provided to control or fix the released or closed position of the throttle.

The casing of my improved air intake valve 9, as viewed in an inverted position in Figure 2, comprises a cylindrical housing 15 provided with a bore of three different diameters. The lowermost bore section 16 constitutes the air intake port of the valve which is of sufficient cross sectional area to admit the greatest amount of air required. If desired, an air filter casing containing any suitable filtering material may be threaded on the lower end of the housing 15 as shown in said application.

The bore section 16 communicates with a slightly larger diameter long bore section 20 in which operates the valve 21 of my invention. The valve has a sliding fit in the bore section 20 and is of substantially the same length as indicated to provide for a large amount of movement between its closed end fully open positions and to provide for a certain amount of inertia. The lower or front end of the valve 21 is conical as at 22 to seat on a conical seat 23 formed on the shoulder between the bore sections 16 and 20. The outer face of the valve is provided with pairs of diametrically oppositely located air-metering grooves 24, 25 and 26 of different lengths and of increasing depths from a point near the upper or rear end of the valve toward the lower or front end of the valve so as to admit a small amount of air past the inner or rear end of the bore section 20 when the valve is first moved away from its seat and increasing amounts of air as the movement of the valve away from its seat is continued by stronger suction in the manifold. The grooves may be of the same depths at the lower or front end of the valve.

The upper end of the cylindrical housing 15 is closed by a member 27 which has an enlarged head 28 on its lower end threaded as indicated into the upper large section 29 of the bore in the housing 15 whereby the member 27 and the housing 15, which together constitute the valve casing, may be relatively adjusted toward and away from each other for controlling the spring pressure on the valve.

The member 27 is threaded at its upper end

as indicated at 30 for threaded engagement in a hole in the intake manifold 7.

The member 27 is provided with a through-bore, the upper end section 31 of which is of sufficient size to permit the largest amount of air required to pass therethrough into the intake manifold. The lower end section of the bore is enlarged as at 32 to provide an axial recess to receive one end of a weak valve seating spring 34. The lower end of the spring 34 is seated in a long axial recess 35 in the valve 21.

The lower end of the enlarged bore section 32 terminates in one or more transverse grooves 36 extending diametrically and laterally beyond the outer face of the valve and of no greater width than the diameter of the enlarged section 32 of the bore which is of less diameter than that of the valve with the result that when the upper end of the valve 21 is forced against the lower end of the member 27, air will be permitted to pass by the valve into the bore 32, etc. The member 27 may be screwed far enough into the housing 15 to engage and seat the valve 21 as shown in Figure 2.

Projecting upwardly from the bottom of the recess 35 in the valve 21 is a rod 40 which is provided with fins or threads as indicated at 41 for steadyng the movements of the valve and preventing it from responding to slight variations from the mean of the suction pressure established in the intake manifold under any given unchanging conditions of operation. The inrushing air impinges on the fins or threads and exerts a slight inward pull or drag on the valve and functions as a brake against an outward movement of the valve due to slight decreases at frequent intervals in the suction pressure such as occurs in the operation of the engine at a so-called constant suction pressure. The valve is, therefore, open the required amount when the suction pressure increases to the mean to admit the proper amount of air.

For the purpose of locking the valve in adjusted position I provide the stem of the member 27 with threads to receive a lock nut 45 which in all positions of adjustment may be drawn up against the upper or rear end of the housing 15. The cooperating threads on the head 28 and the housing 15 are preferably of small pitch, such as sixteen threads to the inch as shown in Figure 5, to provide for a fine adjustment of the spring and valve. The cooperating threads on the member 27 and the lock nut 45 are preferably of a slightly smaller pitch, such as eighteen to the inch as shown in Figure 5, and both sets of cooperating threads are preferably of the same turn or direction so that the parts may be locked in adjusted position by seizing the lock nut 45 and housing 15 and turning them clockwise after the lock nut has been advanced against the housing. The lock nut is released by turning both the lock nut and the housing 15 counter-clockwise.

The valve is in the locked closed position when it is mounted in position on the manifold or in a vacuum line. It is preferably mounted in a vertical position. After the valve has been so mounted, the engine is started and idled until it is warmed. The housing 15 is then backed up by a counter-clockwise movement until the engine misses or fails to fire evenly. The housing 15 may then be turned clockwise a short distance, or a

minor readjustment may preferably be made of the idle jet screw on the carburetor (not shown) until the firing is again even, after which the lock nut is advanced against the housing and both the housing and the lock nut are then turned clockwise to lock the parts in adjusted position. Further minor adjustments may be made of the valve if found desirable for better performance at cruising speeds.

While I have described this invention with reference to a preferred embodiment illustrated, it is to be understood that I reserve the right to all such changes as fall within the principle of this invention and the scope of the appended claims.

I claim:

1. An air intake valve consisting of a valve casing, comprising, in series, an inlet passage, a valve seat, a guide chamber of larger diameter than the inlet passage, a second chamber of larger diameter than the guide chamber and an outlet passage, and a piston valve slidable in the guide chamber and biased toward closed position, said valve having a head co-acting with said seat, said valve having two identical sets of grooves of different lengths, extending longitudinally from the head, in which the grooves of same lengths are disposed at opposite ends of a diameter and in which all of the grooves are tapered with their largest cross section adjacent to the head and in which all of the grooves terminate within the guide when the valve is seated.
2. An air intake valve consisting of a valve casing, comprising in series in axial alinement an inlet passage, a valve seat, a guide chamber of larger diameter than the inlet passage, a second chamber of larger diameter than the guide chamber and an outlet passage, and a piston valve slidable in the guide chamber and biased toward closed position, said valve having a head adapted to co-act with said seat, and provided in its outer face with grooves of increasing cross section toward said head, and a rigid axial reduced extension on the inner end of the piston projecting into the outlet passage and provided with transversely extending ribs projecting toward but spaced from the interior wall of the outlet passage.
